(57) **CLAIM**

The ornamental design for a dog training assembly, as shown and described.

DESCRIPTION

FIG. 1 is a front, right and top perspective view of a dog training assembly showing my design.

FIG. 2 is a front, right and top perspective view of a remote controller of the dog training assembly of FIG. 1.

FIG. 3 is a rear, left and bottom perspective view of the remote controller of FIG. 2.

FIG. 4 is a front elevation view of the remote controller of FIG. 2.

FIG. 5 is a rear elevation view of the remote controller of FIG. 2.

FIG. 6 is a left side elevation view of the remote controller of FIG. 2.

FIG. 7 is a right side elevation view of the remote controller of FIG. 2.

FIG. 8 is a top plan view of the remote controller of FIG. 2.

FIG. 9 is a bottom plan view of the remote controller of FIG. 2.

FIG. 10 is a front, right and top perspective view of a collar of the dog training assembly of FIG. 1.

FIG. 11 is a rear, left and bottom perspective view of the collar of FIG. 10.

FIG. 12 is a front elevation view of the collar of FIG. 10.

FIG. 13 is a rear elevation view of the collar of FIG. 10.

FIG. 14 is a left side elevation view of the collar of FIG. 10.

FIG. 15 is a right side elevation view of the collar of FIG. 10.

FIG. 16 is a top plan view of the collar of FIG. 10; and,

FIG. 17 is a bottom plan view of the collar of FIG. 10.

The broken lines shown in the drawings are included for the purpose of illustrating portions of the dog training assembly that form no part of the claimed design.

1 Claim, 17 Drawing Sheets
